UNITED STATES PATENT OFFICE

98,566

DESIGN FOR A SWEATER OR SIMILAR ARTICLE

Leo B. Helfgott, Brightwaters, N. Y.

Application November 26, 1935, Serial No. 59,765

Term of patent 14 years

To all whom it may concern:

Be it known that I, Leo B. Helfgott, a citizen of the United States, residing at Brightwaters, L. I., in the county of Suffolk and State of New York, have invented a new, original, and ornamental Design for a Sweater or Similar Article, of which the following is a specification, reference being had to the accompanying drawing, forming part thereof.

In the drawing:

Figure 1 is a front view of a sweater showing my new design, the neck being unbuttoned and open.

Figure 2 shows the sweater of Figure 1 buttoned at the throat.

Figure 3 is a fragmentary view showing the collar turned up.

The entire sweater is knitted as shown at the neck line. The back of the sweater shown is plain or conventional.

The characteristic feature of my design resides in the association or combination in a single garment of the collar insert with the substantially V-necked sweater to simulate twin sweaters with a double collar as shown.

I claim:

The ornamental design for a sweater or similar article, substantially as shown and described.

LEO B. HELFGOTT.
